MERCURY TUBE SWITCH

Carl H. Larson, Elkhart, Ind., assignor to The
Adlake Company, a corporation of Illinois

Application April 24, 1935, Serial No. 17,964

7 Claims. (Cl. 200—112)

This invention relates to mercury tube switches in which the level of the mercury is determined by the position of a displacer and that is dependent upon a magnetic core in the tube subject to a magnet and the principal object is to make it easy to inspect the electrodes and their relation to the mercury while assembling the switch, and when it is in service. This is achieved by using a very buoyant and transparent displacer of glass, for example assembling, carrying a magnetic core above the parts to be seen. Incidentally, this keeps the metal of the core from affecting the mercury and contributes to other advantages which will appear as the description is read in connection with the accompanying drawing, in which

Fig. 1 is a vertical section through one form of power transfer switch embodying the invention, with the parts shown in the position they assume when the magnet is de-energized and the displacer is floating in the mercury;

Fig. 2 is a section of the same switch with the parts in the position they assume when the magnet is energized and the displacer is lifted;

Fig. 3 is a perspective view of the displacer and the magnetic core;

Figs. 4, 5 and 6 are views similar to Figs. 1, 2 and 3, but disclosing a different form of power transfer switch embodying the invention.

But this drawing and the description are used for the purpose of disclosure only, and others will be able to make different forms and apply various features of the invention to use in other switches.

The mercury switch includes a glass tube or envelope 10, pinch sealed at the bottom 11 and sealed off at the top 12, after being given a charge of mercury 13 and a suitable gas fill, such as helium, helium hydride, hydrogen, etc.

Three conductors, 14, 15 and 16, are sealed through the bottom, and the last two are insulated from the mercury by sleeves 17 and 18, different heights beyond which they are exposed.

The displacer is a transparent tube 19 which, in this power transfer switch, takes the form of an inverted test tube, or thimble, having a closed upper end 20 and a wide open lower end 21, the latter receiving the conductor 15 and sleeve 17 in the position shown in Fig. 1.

The magnetic core, or armature 22, of some ferrous material is a hollow cylinder having rounded hardened steel guides 23 pressed into it adjacent to its opposite ends and serving to permit ready flow of gas fill, or mercury, while guiding the core along the glass.

The core is preferably made of exceptionally pure iron, such as, for example, Svea metal, sold in the United States by the Swedish Iron and Steel Company, of New York, but of course other ferrous material will be selected to suit conditions of service.

A spring 24 of piano wire, coated with magnetic oxide of iron, or degassed pure iron, is screwed into the bore 25 of the core and has several turns 26 close together to bind it securely in the core. The upper portion of the core is counter-bored at 27, and the spring 24 projects beyond the upper end to prevent the core from striking the top portion 12 of the glass envelope while the switch is being shipped or handled.

Another coil spring 28 extends across the bottom of the tube 10 about the sleeve 17, and acts as a cushion for the lower end 21 of the displacer tube 19.

The lower end of the core 22 has a reduced hollow nipple 29 into which the upper closed end 20 of the displacer is inserted. Ordinarily the friction of a slight taper will be sufficient to maintain the assembly, but the tube may be cemented in place with silica, if desired.

In order to permit mercury to escape from the bore of the armature after the switch has been on its side, diagonal cuts 30 are made in the armature with a milling cutter, beginning at about the juncture of the nipple 29 with the main body 30 of the armature.

Should the armature be made split, as is sometimes done for use with alternating current, these cuts may be omitted.

The electromagnet associated with the switch 35 includes a coil 31, a laminated yoke 32, preferably of Allegheny transformer steel, and pole sleeves 33 of pure soft iron, such as Svea metal, held in place by iron clamps 34.

The mercury tube switch is adjustably held 40 within the core by a split ring 35 of spring brass located between the adjacent ends of the pole sleeves 33, and frictionally holding the glass tube 10.

The displacer 19, being transparent from the lower end of the nipple 29 to the bottom 21, the height of the charge of mercury in relation to the electrodes formed by the exposed end of the conductors 14 and 15, can be adjusted by sight 45 during the assembly operation, and afterwards in use the electrodes and the height of the mercury can be inspected at any time by direct vision.

The displacer should be made of heat resisting glass of which there are a number on the market 50

known as boro-silicate glass, Pyrex, etc., or where the cost will permit, it may be made of quartz.

In Fig. 1 the displacer, trapping gas within it, forces the mercury away from the exposed end 5 of the conductors 15 and raises the level above the sleeve 18 and closes the circuit between the conductor 14 and the exposed end of the conductor 16.

Upon the magnet being energized, the armature 10 lifts the displacer to about the position shown in Fig. 2, the mercury rises about the exposed end of the conductor 15 and falls below the exposed end of the conductor 16, thereby opening the circuit from the conductor 14 to the conductor 16, 15 and closing the circuit from the conductor 15 to the conductor 14.

Such switches are used to transfer from one source of power to another and, of course, the one circuit must be broken before the other circuit 20 is closed. That is easily accomplished with the switches here disclosed and at the same time the volumes are reduced to such a small extent that very little power is used to operate the switch.

As an example of dimensions, one form of 25 switch that has been found satisfactory has a tube 10, 138 mm. long, 15½ to 16 mm. inside diameter. The conductor 15 extends 27 mm. above the bottom of the tube at the inside and is exposed for a length of 5 mm. and the conductor 16 extends 30 34 mm. above the bottom of the tube and is also exposed for 5 mm.

The armature is 1½ inches long, 7/16 inches inside diameter, and the counter bore is ½ inch in diameter for a depth of 1/8 inches. Other dimensions are in proportion.

In the form shown in Figs. 4, 5 and 6, a glass tube, or envelope 36, is similar to the glass tube 10, except that it has a lateral enlargement 37 at the bottom to provide space for the conductor 40 16 by which means a relatively small tube serves for a three-electrode switch, and provides ample clearance for all parts.

The displacer tube, or thimble, 38, is longer than the tube 19, and the core, or armature 39, 45 is a split sleeve telescoped over the displacer and provided with fingers 40 at its ends, making contact with the outer surface of the tube, or being spaced from it very slightly.

A spring 41 of degassed pure iron fits tightly 50 over the upper end of the thimble 38, and the tips of the fingers 40 are wedged between the adjacent convolutions of the coil.

In assembly the armature and the spring are gotten into the position shown in the drawing by 55 a threading movement, the displacer tube is inserted from below and pressed upwardly while being turned, which has the effect of threading the coil onto it, where it remains securely by the clamping friction.

When the magnet is de-energized the parts assume the position shown in Fig. 4, the displacer forcing the mercury away from the exposed end of the conductor 15 before it rises to cover the 60 exposed end of the conductor 16.

When the magnet is energized, the parts assume the position shown in Fig. 5, the circuit from the conductor 14 to the conductor 16 being first broken and then the circuit from conductor 70 14 to conductor 15 closed.

It will be obvious to those skilled in the art that the construction here illustrated provides the necessary clearances with a minimum vol-

ume of mercury and a very small power consumption.

For alternating current service, the armature 39 is cold rolled steel, case hardened and ground or some similar material whereby the armature 5 requires no guide and can be gotten very close to the magnet. For direct current service, soft iron should be used and guides provided, as explained in the co-pending application of Gehrand and Larson, filed April 18, 1935, Serial Number 10 17,053.

I claim as my invention:—

1. In a mercury tube switch, a tube, a conductor sealed through the bottom of the tube and provided with an electrode within the tube, mercury in the tube to co-operate with the electrode, a hollow transparent displacer cooperating with the mercury and adapted to cover the electrode and a hollow magnetic core carried by the displacer and arranged so that a side view of the 20 electrode is possible through the transparent displacer.

2. In a mercury tube switch, a tube, a conductor sealed through the bottom of the tube and provided with an electrode within the tube, mercury 25 in the tube to co-operate with the electrode, a tubular displacer substantially closed at its upper end adapted to telescope over the electrode when depressed into the mercury, and a hollow magnetic core carried by the displacer at all times 30 above the mercury level.

3. In a mercury tube switch, a tube, conductors sealed through the bottom of the tube, mercury in the tube, an insulating sleeve surrounding one of the conductors for a space above the 35 bottom of the tube, a tubular displacer closed at its upper end and aligned with the last mentioned conductor whereby in one position it will displace mercury from that conductor, and a magnetic core borne by the displacer at all times 40 above the mercury level.

4. In a mercury tube switch, a tube, conductors sealed through the bottom of the tube, mercury in the tube, an insulating sleeve surrounding each of the two conductors for a distance above the 45 bottom of the tube, a transparent tubular displacer having a pocket open at its bottom and adapted in one position to displace mercury from one of the conductors and a magnetic core carried by the displacer above the mercury level. 50

5. In a mercury tube switch, a tube, mercury therein, conductors sealed through the tube for co-operation with the mercury, a tubular displacer open at its bottom to the mercury and closed above, and a magnetic core carried by the 55 displacer above the mercury.

6. In a mercury tube switch, a tube, mercury therein, conductors sealed through the tube for co-operation with the mercury, a displacer comprising a glass tube closed at the top and open at 60 the bottom to trap gas above the mercury, and a magnetic core fixed to the displacer above the mercury.

7. In a mercury tube switch, a tube, conductors sealed through the bottom of the tube, mercury in the tube, an insulating sleeve surrounding one of the conductors for a distance above the bottom of the tube, a transparent tubular displacer open at its bottom and adapted to telescope over said one conductor, and a magnetic core carried by the displacer above the mercury level. 65

CARL H. LARSON.
